CLAIM

The ornamental design for a dashboard with screen for vehicle, as shown and described.

DESCRIPTION

FIG. 1 is a front view of a dashboard with screen for vehicle showing my new design;

FIG. 2 is a back view thereof;

FIG. 3 is a left side view thereof;

FIG. 4 is a right side view thereof;

FIG. 5 is a top view thereof; and,

FIG. 6 is a perspective view thereof.

The broken lines illustrate portions of the dashboard with screen for vehicle which form no part of the claimed design.
